CROSSBAR SWITCH

Charles Gillings and Lawrence John Murray, Liverpool, England, assignors, by mesne assignments, to Automatic Electric Laboratories, Inc., Chicago, Ill., a corporation of Delaware

Application December 26, 1942, Serial No. 470,158
In Great Britain February 27, 1942

13 Claims. (Cl. 179—22)

The present invention relates to novel methods of employing crossbar switches in telephone or like systems and has for its object arrangements by which the number of crossbar magnets and contact sets required for a given size of exchange or switchboard may be kept at a low value. The kind of crossbar switch to which the invention relates is one in which a preparatory operation corresponding to a row of contact sets is first made and subsequently a holding operation common to a column of contact sets is made whereupon a particular contact set corresponding to that which belongs both to the row and to the column, for which preparatory and holding operations have been made respectively, is operated. When this type of crossbar switch is used in automatic telephone circuits it is usual to employ two of such switches for a group selecting stage or for a combined preselecting and final selector stage and it is one of the features of the present invention to extend the application of a single crossbar switch to such conditions by arranging that instead of one preparatory operation only being effected two are effected whereby a connection can be established between contacts in different rows.

According therefore to one feature of the invention in automatic telephone or like systems a crossbar switch is employed in which a through connection is effected by two distinctive preparatory operations of the mechanism of the switch followed by a holding operation, which holding operation is determined independently of both distinctive preparatory operations. For instance, one preparatory operation may depend upon the line of a subscriber taking part in the connection and the other preparatory operation may depend upon whether the said subscriber's line is calling or being called, while the holding operation is dependent upon which of a number of lines in an outgoing or incoming group the connection is to be made with; this applies to a single crossbar switch employed as a combined preselector and final selector switch. Or again one preparatory operation may depend upon the line over which connection is made to said switch and the other preparatory operation may depend upon which of a number of groups of lines outgoing from said switch connection is to be made with, while the holding operation depends upon which line of the selected group connection is to be made with. Such a crossbar switch can be used as a group selector.

A further feature of the invention consists of an automatic telephone or like system employ-

ing crossbar switches in which a group of subscribers' lines and groups of incoming and outgoing links are connected to a single crossbar switch by which a through connection can be made between any line of a group which is calling or being called and any outgoing or incoming line over which a call may be or is being set up, a group selection being also effected by a single crossbar switch by which a through connection can be made between any of a number of lines incoming to the switch and any line of a number of groups of lines outgoing from the switch whereby a complete connection can be set up employing a single crossbar switch for the pre-selecting and each numerical stage.

The invention will be better understood from the following description of one method of carrying it into effect reference being had to the accompanying drawings comprising Figs. 1-10.

20 Of these figures Fig. 1 shows the essential trunking arrangements of a crossbar private automatic exchange board, hereafter termed P. A. X board, which has a capacity of up to 100 lines. Fig. 2 shows the cross connection arrangements between the various 20 line groups and the five link switching units on the board. Figs. 3-10 when arranged in the manner shown in Fig. 6 show the circuits of the board.

Referring now to the trunking diagram Fig. 1, 30 the 100-line board comprises a number of 20-line groups up to five as a maximum, and bearing the two digit numbers 11-20, 31-40 up to 91-00. For each set of 10 lines a small crossbar unit or so-called subscriber switching unit SSU is provided, these units being grouped together in pairs. The two units SSU₁ and SSU₂ serving subscribers 11-10 and 21-20 respectively are shown with special reference to outgoing calls, while the units SSU₆ and SSU₁₀ serving subscribers 40 91-90 and 01-00 are shown with special reference to incoming calls.

For the purpose of effecting connection between calling and called 10-line subscriber units, five crossbar link switching units LSU₁-LSU₅ are 45 provided, the first of which is shown more fully in Fig. 1, and it will be seen from Figs. 1 and 2 that four connecting link circuits AL-DL, in which are provided the battery feeding and ringing relays, etc., are associated with each 50 link switching unit; through each such unit up to four connections can extend at any one time, although in common with other crossbar switching units it will be appreciated that such calls are not set up simultaneously. For each 20-line 55 group comprising a pair of subscriber units such

as SSU1 and SSU2 there are provided four outgoing links and also four incoming links. The outgoing links from all subscriber units are distributed over the five link switching units LSU1-LSU5 in the manner shown in Fig. 2 while the incoming links are available from the outgoing side of each of the five link switching units on the board. The arrangements are such that a maximum of four connections can be extended through each subscriber unit, which connections may comprise either four outgoing or four incoming connections or so many outgoing and so many incoming connections, the total not exceeding four. Up to eight connections can be handled by each pair of subscriber units subject to a maximum when four outgoing and four incoming connections are involved. These arrangements enable the board to provide a high grade of service at reasonable cost, but it will be understood that the invention is not limited in scope to the precise number of links stated as this may be altered to suit the traffic requirements involved.

Reviewing now the essential construction of the various crossbar subscriber units SSU1-SSU10, these each comprise ten horizontal "operate" bars and the associated bar-controlling relays 1SP-10SP which connect with the ten subscribers' lines concerned and also four vertical "hold" bars and the associated relays ASH-DSH which control the extension of the four possible incoming and/or outgoing connections which can extend through the unit. Two further horizontal "operate" bars are also provided under control of relays IP and OP which serve to prepare for the connection of the unit to an incoming or outgoing link respectively. The arrangements are such that when a call is originated the relevant SP relay is operated, after which if there is a free outgoing link to a link switching unit the OP relay is operated. The connection of the calling party to the link is then completed by the operation of the vertical "hold" relay associated with the particular free outgoing link selected, the vertical "hold" bar providing in effect an internal link within the calling subscriber unit. The connection of an incoming link to a subscriber is effected in similar manner except that relay IP is operated this time in addition to the relevant SP relay, after which the vertical "hold" relay associated with the particular link calling is operated to provide the necessary internal link within the called subscriber unit.

As regards the link switching units, these each comprise four horizontal "operate" bars and the associated relays 1CP-4CP with each of which a connecting link circuit is associated. Five additional horizontal "operate" bars and associated relays 1TP-5TP are provided for the purpose of selecting the particular set of links incoming to the required 20-line subscriber group, the particular one of these relays to be operated being determined in accordance with the tens digit of the particular number dialled. For instance, for a tens digit 1 or 2, relay 1TP will be operated to prepare for connection to any one of the four links connecting with the first 20-line group on the board, that is to say the subscriber units SSU1 and SSU2, while if a tens digit 9 or 0 is dialled then relay 5TP will be operated to prepare for connection to any one of the four links extending to the 20-line group comprising subscriber units SSU9 and SSU10. Each link switching unit may therefore be said to constitute a five-level four outlet per level, group selector switch which

is actuated under external control from suitable common equipment which will be later described. Further, owing to its crossbar construction it is capable of handling up to four connections at the same time, the four vertical bars providing internal links between the calling connecting link circuits and the links taken in use leading to the called 20-line groups.

In order to prevent the various links involved in a connection from being confused with one another, it is proposed that the links which terminate at one end on the outgoing side of the subscriber switching units and at the other end on the incoming side of the link switching units, and which will each include a connecting link circuit, shall be termed "out" links; and that the other links which terminate at one end on the outgoing side of the link switching units and at the other end on the incoming side of the subscriber switching units, shall be termed "in" links. The vertical bar links within the subscriber switching units and within the link switching units may be generally described as internal vertical bar links of the switching unit in question.

Referring now to the circuits of Figs. 3-10, for the purpose of associating a free "out" link with a calling line, common equipments PCE1 (Fig. 7) and PCE2 (not shown) are provided for the two respective groups of 50 subscribers' lines served by the board. The line circuit of subscribers No. 11 together with sufficient parts of the line circuits of other of the 49 subscribers 12-50, in the first 50-line group as will enable the arrangement to be understood are shown in Fig. 3. From reference to the line circuit of subscriber No. 11 it will be noted that as previously mentioned, the line of this subscriber will connect with the horizontal bar relay 1SP of the crossbar subscriber switching unit SSU1, which relay 1SP serves as the subscriber's line relay so that each subscriber will only require a single individual cut-off relay such as 1K in addition. The primary control equipment PCE1 is provided with a rotary switch of the self-interrupted drive type which is adapted to select a free one of the four possible "out" links to which the subscriber group in which the calling party is located has access and thereafter to cause the crossbar subscriber switching unit in question to switch through to the selected link. Fig. 4 shows a connecting link circuit such as AL of Figs. 1 and 2 which is assumed to be associated with the first of the four links accessible to subscriber units SSU1 and SSU2 while Fig. 5 shows circuits of the link switching unit LSU1 and its associated controlling relays. Common to each of the five link switching units on the board are the secondary control equipments SCE1-SCE5 shown in Fig. 2, circuits of SCE1 being shown in Figs. 8, 9 and 10 and being accessible over common leads from each of the connecting link circuits AL-DL associated with link switching unit LSU1.

On the taking into use of the circuit AL; this is connected over common leads with equipment SCE1 common to the connecting link circuits AL-DL of the unit LSU1 while the unit LSU1 horizontal bar associated with the calling link is actuated to prepare for connection to any one of the four available "in" links to the required 20-line group which may be selected.

The dialling of the tens digit of the called number into equipment SCE1 enables the required group of "in" links to be determined and at the end of this digit, connection to the selected group is prepared for by the operation of the

relevant TP relay which actuates its horizontal bar. At this stage therefore the horizontal bar associated with the calling "out" link and the horizontal bar associated with the selected group of "in" links are both actuated but no connection can be effected therebetween until the vertical hold bar representing the internal link within the unit is operated.

The dialling of the units digit enables the required subscriber's line to be ascertained and tested from equipment SCE1 and, if found to be free, to be connected with via the unit LSU1 and the subscriber unit in which the line is located. In order to prevent more than one connection being in process of being set up through a subscriber unit at a time and so to prevent multiple connection to an outlet, the above-mentioned switching-through operation is controlled by a so-called final switching control equipment FSC, common to the board, which is accessible to the SCE equipment in question when both tens and units digits have been dialled. The equipment FSC on being taken into use initiates testing for a free one of the four available "in" links to the called 20-line group as determined by the particular tens digit dialled, the testing arrangements being so devised that an "in" link will not test free unless the corresponding internal link within the unit LSU1 is also free, this being necessary since it is possible that the internal link might already be in use on a connection to some other 20-line group. If a free "in" link together with a free corresponding internal link in the unit is encountered, then the relevant vertical bar will be actuated to effect the necessary internal connection between the calling "out" link and the seized "in" link. At the same time a signal is sent forward via equipment SCE1 to operate the incoming relay IP of the called subscriber unit of the pair sharing the four "in" links and on which the called party is located, whereupon the associated horizontal bar is actuated. The equipment SCE1 is also adapted at this stage to test the called line and if it is found to be free, then the associated line relay is operated and actuates its horizontal bar. When the testing relay in the equipment SCE1 operates to indicate that the called subscriber is free, the called subscriber unit vertical bar internal link associated with the seized "in" link is actuated to connect the "in" link through to the called subscriber at the subscriber unit, and since the calling "out" link will have already been connected through to the other end of the "in" link at the link switching unit, the connection between the calling and called parties will be complete and the common equipments SCE1 and FSC are released for further common use.

Further details of the operations will become apparent from the following circuit description.

Reviewing the general nomenclature of the various elements used in the circuits, it will be seen that the number of contact units carried by each relay is shown underneath its designation as for instance relay

1K
3

(Fig. 3), and these contact units are designated individually in small letters which in this instance will be $1k_1$, $1k_2$ and $1k_3$. A slow-to-release relay is shown with a hatched portion at one end of the rectangle indicative thereof, while a slow-to-operate relay with a copper slug at the armature end of its core is shown with a cross at one

end. The contact units individual to the crossbar switch vertical and horizontal relays are indicated in the same manner, while the set of crossbar switch contacts proper which are closed at the intersection of any given pair of vertical and horizontal bars are designated

IP SP
ASH' ASH . . . etc.

10 according to the particular crossbar relays involved.

The various rotary switches such as that in the common equipment of Fig. 7 which is designated HS are provided with driving magnets such as HM each having a set of interrupter contacts such as hm . The various sets of wipers and banks thereon are designated HS1 and HS2 etc.

15 Considering now the circuit operations, it will be assumed for the purpose of the description that subscriber No. 11 originates the first call on the P. A. X board in which case the loop placed via his telephone across the left-hand top set of incoming negative and positive conductors (Fig. 3) operates the combined line relay and crossbar magnet ISP of the subscriber unit SSU1 over the following circuit: battery, resistance YA, chain-connected contacts isp_4 - $10sp_4$ of the relays ISP-10SP on the unit SSU1, contacts tk_1 and isp_2 , upper winding of relay ISP, contacts tk_4 , negative line, subscriber's instrument, positive line, contacts $1k_2$, common lead 9 on to which the positive lines of all ten of the subscribers 11-10 are connected, contacts of the vertical hold relays ASH-DSH in the two subscriber units SSU1 and SSU2 having access to the same group of four "out" links and common lead 10 to earth via contacts ics_8 of relay ICS in the final switching control equipment FSC of Fig. 8.

20 Relay ISP in operating at first operates contacts isp_1 to complete a local locking circuit for itself via resistance YA independent of the chain circuit, and it also operates its associated horizontal bar on subscriber unit SSU1, while at contacts isp_3 it extends a guard earth to the incoming test lead T. It will be noticed that five relays IS-5S are provided in association respectively with the sets of ten SP relays of the subscriber units SSU1-SSU5, and in the present instance relay ISP of subscriber unit SSU1 in operating completes an operating circuit for relay IS over the following circuit: earth, resting contacts ics_6 , common lead 8, resting contacts $1s_2$ - $5s_2$, resting contacts $5s_3$ and $1s_3$, winding of relay IS and operated contacts isp_4 to battery via resistance YA. Relay IS in operating in a manner to be described serves to ensure that the hunting switch HS in the common unit of Fig. 7 shall only test on to the group of four "out" links to which the subscriber units SSU1 and SSU2 have access, while at contact $1s_1$ it first completes a local locking circuit for itself and at contacts $1s_2$ and $1s_3$ it disconnects any operating circuit for the relays 2S-5S of the non-calling subscriber units SSU2-SSU5 in case subscribers on these units endeavour to call at this time, it being necessary to ensure that only one call shall be in process of being set up at any one time on a group of crossbar units served by one common equipment. At contacts $1s_2$ it also completes a circuit to relay SA which is common to all fifty subscribers associated with subscriber units SSU1-SSU5 and serves to initiate the operation of the common equipment of Fig. 7.

25 30 35 40 45 50 55 60 65 70 75 774

Relay SA, which, although shown in Fig. 3, really forms part of the equipment of Fig. 7, in

operating at its contacts *sa1* (Fig. 7) completes a self-interrupted driving circuit for the magnet HM of hunting switch HS and at contacts *sa2* prepares a circuit for the outlet testing relay TK, while at *sa3* (Fig. 8) it disables the equipment FSC for a reason to be later described. The switch HS3 has access to three groups of "out" links over its wiper and bank HS3 but the arrangements are such that relay TK can only test over the particular one of these three groups with which the calling party is permitted to be associated, the selection being determined by the particular S relay operated. With relay *1S* operated, relay TK is only connected up to wiper HS3 when the switch HS is in any one of the positions 1-4 where it gains access to the first group of "out" links, while if relay *2S* were operated the same remarks would still apply, since subscriber unit SSU2 also has access to this same group of links, excepting that in this instance access to the group is had over HS3 bank contacts 5-8. If relay *3S* were operated then access would be possible to the second group of links over HS3 bank contacts 9-12. In the present instance with relay *1S* operated and with the HS switch wipers in position 1, a testing circuit is completed from earth via the winding of relay TK, contacts *sa2*, wiper HS2 on bank contact 1, contacts *ash5* and *1s4* and wiper HS3 on bank contact 1 which extends over the first of the four "out" links accessible to subscriber No. 11 to connecting link circuit AL shown in Fig. 4. It is assumed in the present instance that this link circuit is disengaged so that the corresponding "out" link will also be disengaged and it will be marked free by a resistance battery potential extended thereto from the secondary control equipment SCE1 of Figs. 8-10, which, as previously described, is common to the link switching unit LSU1 with which four connecting link circuits including link circuit AL are terminated. The idle marking battery potential extends from battery via resistance YH (Fig. 8), contacts *n1* and *ba1*, common lead *16*, and contacts *sd2* and *se3* (Fig. 4) on to the test lead P of the "out" link in question. Relay TK (Fig. 7) quickly operates in series therewith and at its contacts *tk1* opens the energising circuit of magnet HM before it has time to operate so that the HS switch wipers will remain in position 1.

If link circuit AL proves busy, then an earth potential will be fed back over the P lead to prevent relay TK from operating and the HS switch magnet will operate in a self-interrupted circuit to drive the wipers on to the next position 2 where the testing operation will be repeated and so on. If all the connecting link circuits accessible to subscriber No. 11 prove busy, then the HS switch will continue rotating and in each revolution will test the four outlets accessible to this subscriber until one becomes available. Alternatively, it might be arranged that switch HS after testing the four relevant outlets and finding them busy would proceed to an unused position and thereupon bring about the operation of a relay to return a busy tone to the subscriber who would have to bang up his receiver and call again later.

If link circuit AL is free, relay TK operates and at its contacts *tk1* brings up relay TKR which at its contacts *tkr1-tkr5* (Fig. 3) opens the initial energising circuit of all SP relays, and at contacts *tkr7* completes a circuit over operated contacts *1s5* to operate the subscriber unit SSU1 outgoing "prepare" relay OP. This relay in operating

actuates its associated horizontal bar on subscriber unit SSU1 to prepare for connection of the "out" link to link circuit AL and at its contacts *op1* (Fig. 7) extends earth over wiper HS1 in position 1 to bring up the subscriber unit SSU1 vertical "hold" relay ASH associated with the first "out" link. Relay ASH in operating actuates its associated vertical bar so that the sets of crossbar contacts at the intersection of the vertical and two horizontal bars in question will be operated. These are shown as

SP
ASH and *OP*
ASH

in Fig. 3, and are numbered 1-3 and 1-4 respectively, the contacts 1-3 in closing extending the calling line circuit through to the connecting link circuit taken into use. Relay ASH in operating also at contacts *ash5* opens the initial operating circuit for relay TK (Fig. 7) but this relay is held via contacts *ash6* (SSU1) (which make before contacts *ash5* open) and *tkr6* to battery via resistance YG. The operating earth for relay ASH extends over contacts *ash1* to the P lead to guard the seized link and also extends over sets of crossbar contacts

OP
*ASH*³ and *SP*
*ASH*³

to bring up the calling party's cut-off relay *1K*. This relay in operating at contacts *1k1* and *1k2* removes the line relay *1SP* from across the speaking leads and this relay releases while at *1k3* it maintains the guard earth on the incoming test lead T so as to maintain the busy marking of the calling line. Relay *1SP* in releasing opens the holding circuit of relay *1S* at contacts *1s4* and this relay commences to release slowly due to its slug.

The extension of the calling loop through to link circuit AL brings about the operation of relay A therein and this relay in turn brings up relay B in series with rectifier MRA and resistance YF. Relay B in operating locks over its contacts *b1*, at *b2* extends earth forward to operate the horizontal "prepare" relay *1CP* (Fig. 4) associated with link circuit AL and located on link switching unit LSU1. At contacts *b3* dial tone is connected up to the centre winding of relay A over the following circuit: common lead *25* (Fig. 8) on to which an earthed dial tone source is extended, contacts *n3*, common lead *21*, and contacts *sd5*, *b3*, *se4* and *f2* to the winding of relay A, diaj tone thereupon extending by induction through the windings of relay A on to the speaking conductors. At contacts *b4* a guarding and holding earth potential is extended on to the link test lead P, and this earth extends back to hold the cut-off relay *1K* of the calling line circuit and relay ASH before relay *1S* has had time to release. On release of relay *1S*, the holding circuit of relay SA is opened at contacts *1s2*, while at contacts *1s5* (Fig. 7) relay OP releases the associated horizontal bar. The pin or its equivalent which is engaged by the vertical bar remains held without appreciably restraining the restoration of the horizontal bar. The same remarks also apply in the case of the horizontal bar associated with relay *1SP* and its corresponding pin when this relay is released on the operation of relay *1K*. Relay SA in releasing opens the holding circuit of relays TKR and TK (Fig. 7) and with the release of relay TKR the board is now in readiness to deal with any further calls from

subscribers in the 50-line group catered for by the equipment PCE1.

The unit LSU1 horizontal "prepare" relay 1CP in operating also at its contacts 1cp3, which are shown for convenience in Fig. 4, completes an operating circuit over common lead 19 for relay BA (Fig. 8) in the equipment SCE1, while other contacts 1cp1, 1cp2, 1cp4, further connect the link circuit AL through to the equipment SCE1.

Relay BA in operating at contacts ba1 (Fig. 8) disconnects the idle resistance marking battery from lead 16 extending through to the link P lead and at contacts ba4 extends earth on to the start lead ST of a delay period timing set common to the board, while at ba5 it completes an energising circuit for relay DC over both its windings in series with the tens switch driving magnet DM (non-operative in this condition). Relay DC in operating at its contacts dc1 connects the impulsive lead 20 from the connecting link circuit through via the low resistance winding of relay DC to magnet DM in readiness for the dialling of the first digit of the wanted number.

The calling subscriber No. 11 on hearing the dial tone should now proceed to dial the two required digits of the number, but in case he should neglect to dial and so hold common equipment SCE1 unnecessarily, arrangements are made to release this equipment and to return busy tone to the calling subscriber if dialling does not take place within a predetermined period after seizure. This is effected in the following manner. On the extension of earth to the delay set start lead ST, the delay set is set into operation and soon afterwards applies an earth pulse on to common lead S extending therefrom. Relay TA thereupon operates on its left-hand winding and locks to earth on its right-hand winding, while at contacts ta2 it connects its middle winding and the lower winding of relay TZ up to the Z lead. After a predetermined period an earth pulse is applied from the delay set to the Z lead, whereupon relay TZ comes up on its lower winding in series with relay TA which holds on its middle winding, the initial operating and holding circuits for relay TA being disconnected at contacts ta3 and ta2. Relay TZ in operating at ta1 removes the short-circuit from its upper winding and thereupon locks over this winding in series with resistance YJ, while at ta2 earth is extended over common lead 17 to bring up relay SD in the link circuit. At ta4 earth is extended over common lead 18 to operate relay SE in the link circuit and at ta5 the operating circuit for relay BA is opened. At the end of the Z pulse, relay TZ remains held and relay TA releases and after the slow release period of relay BA, relays TZ and DC are released and the equipment SCE1 is free for further common use. In the link circuit relays SD and SE in operating open the circuit of relay 1CP to dissociate link circuit AL from equipment SCE1 and at contacts sd4 and se4 connect a number unobtainable tone source via common lead 13 to the centre winding of relay A from whence it returns to the calling party who will have to hang up and call again when he decides to set up a connection.

If the calling party commences to dial within the predetermined period after receipt of dial tone, which period is long enough to allow for a reasonable delay in dialling, then on the first release of relay A in the link circuit an energising circuit is completed for magnet DM (Fig. 8) as follows: earth, contacts b1, a1 and 1cp4, lead 20, contacts dc1, low resistance upper winding of relay DC, magnet DM to battery, the winding of re-

lay B being short-circuited during this time, while the lower winding of relay DC is similarly short-circuited in series with resistance YM. On the re-operation of relay A, an energising circuit is re-completed for relay B and relay DC now holds operated on both its windings in series with magnet DM, which will not hold in this condition, and thereupon releases to advance its wipers from contacts 1 to contacts 2. An immediate operating circuit is now completed for relay N over wiper and bank DS1 and contacts ba6 to battery via resistance YK and this relay at its contacts n1 further disconnects the idle marking battery circuit and at n2 opens the holding circuit for relay DC and at the same contacts short-circuits its lower winding so that if there should be no second impulse of the train, relay DC will release after a slow release period governed by the short-circuiting of its winding and will initiate the changeover of the impulsive path from the tens switch magnet DM to the unit switch magnet UM (Fig. 9). In like manner, as described, relay B holds operated during each succeeding break impulse and it will be mentioned here that the presence of the metal rectifier MRA in its energising circuit serves to prevent the slowing up of the operation of magnet DM which would otherwise result by the direct connection of a comparatively low value non-inductive resistance in parallel with its winding; neither the magnet DM nor relay DC moreover will hold operated in series with relay B.

At the end of the first train of impulses, relay A remains operated and holds relay B, while relay DC commences to release slowly, relay N remaining held over wiper and bank DS1. On release of relay DC the impulsive circuit is changed over at contacts dc1 on to magnet UM of units digit switch US, relay UC operating on closure of contacts dc2 in similar manner as for relay DC, and at contacts uc1 completing the impulsive circuit.

In order to avoid the use of ten unit switches for dealing with the units digit of any of the possible ten 10-line groups of subscribers on the exchange, arrangements are made whereby if an odd tens digit is dialled then the units switch will operate over the first half of its bank, while if an even tens digit is dialled the units switch will operate over the second half of its bank. By this means only five units switches are required for the 100 lines. This is effected in the following manner. If in response to an even tens digit the DS switch has been set to any of the positions 3, 5, 7, 9 or 11 or 15, 17, 19, 21 or 23 according as to whether it is operating from its first home position 1 or its second home position 13, then on the release of relay DC during the interdigital pause, earth will be extended via the low resistance winding of relay N (Fig. 8), contacts ba8 and dc3 (Fig. 9), bank and wiper DS2, bank and wiper US2 in normal position, units switch magnet interrupter contact um, and magnet UM to battery. Magnet UM in operating in a self-interrupted circuit thereupon advances the units switch wipers to position 2 after which a self-interrupted driving circuit is completed via contacts ba7 and bank and wiper US2 to advance the wipers to position 13 where the driving circuit is opened at wiper and bank US2. If an odd tens digit is dialled, it will be seen that no driving circuit can be completed for the magnet UM and the US switch wipers will remain on position 1 in readiness for the units digit.

It will be assumed that connection is to be made to subscriber 01 and in response to the dial-

ling of digit 0 the units switch will have been positioned during the interdigital pause to position 13. When the units digit 1 is dialled, relay A in releasing energizes magnet UM and when relay A re-operates at the end of the impulse, magnet UM releases to advance the US switch wipers to position 2. As regards relay UC, during the release of relay A the lower winding of this relay is short-circuited, while on the re-operation of relay A, relay UC maintains itself operated on both its windings in series with magnet UM which will not hold in this condition. Wiper US1 is of the bridging type so that this holding circuit will be maintained until the wiper engages with contact 2 when the lower winding of relay UC will be short-circuited. If only one impulse is involved as in the present instance, relay UC will now commence to release slowly due to its short-circuited winding and on its release the impulsive circuit will be opened at contact uc1. Since relay N will still be held operated over wiper and bank DS1, an energizing circuit will now be completed for relay SGA (Fig. 9) over the following circuit; earth, contacts n6, ba9, jzr2, dc5, uc2 and n5, winding of relay SGA to battery. Relay SGA in operating brings into operation the final switching control equipment FSC (Fig. 8) common to the board, which serves to control the testing of the wanted line and at the same time to ensure that only one connecting link circuit on the board can perform a called line testing operation at any one time, so as to prevent the possibility of multiple connections to one outlet. Relay SGA in operating at its contacts sga3 (Fig. 8) extends earth over common lead 24 to bring up relay FS which in operating at contacts fs2 completes a self-interrupted driving circuit for the magnet SCM of switch SCS in the common equipment and this switch thereupon rotates its wipers in search of a marking indicative of the calling equipment SCE1, which marking comprises battery potential via resistance YL which is extended over contacts sga2 on to bank SCS1. It will be noticed that this marking and the markings of the four other equipments SCE2-SCE5 on the board make multiple appearances in the bank SCS1 and it will be understood that the other banks SCS2-SCS4 are wired in similar manner. In the present instance, since the marking extends on to the first contact of bank SCS1, then as soon as the circuit is completed to relay FK over contacts fs1 this relay will operate immediately and at its contact jk2 will cut the self-interrupted driving circuit for magnet SCM before the magnet has time to energise. At contacts jk1 earth is extended over wiper and bank SCS2 to bring up relay FZ in the equipment SCE1 and this relay at contacts jz3 (Fig. 9) completes a self-interrupted driving circuit for magnet TM of switch TS, the magnet driving circuit extending initially from earth over contacts n6, ba9, jzr2 and jz3, normal contact of TS1, kr1, kr3, tm, TM to battery from earthed low resistance winding of relay N after the TS switch has stepped from position 1.

The function of switch TS is to hunt for a free one of the four possible "in" links to the group of twenty subscribers in which the called subscriber is situated, the group being determined in accordance with the setting of the tens switch DS. The "in" link testing arrangements are moreover such that the wipers of the testing switch TS will only halt on a link having a corresponding vertical bar internal link within the link switch unit LSU1 also disengaged so that the neces-

sary switching through from the calling connecting link via the link switching unit to the free "in" link can be effected. A further point is that for each "in" link in the selected four link group there is a corresponding internal link in each of the two terminating 10-line subscriber units sharing the group, and an "in" link can therefore only be marked free if the corresponding internal link in the called subscriber unit is not in use either on an incoming or an outgoing call and if the corresponding internal link in the other subscriber unit of the pair forming the 20-line group is not in use on an incoming connection, it being appreciated that if the latter internal link is already engaged on an outgoing connection then the "in" link need not be marked busy. This point is taken care of by arranging to provide odd and even test leads for each "in" link, the test lead to be utilised being determined in accordance with the particular tens digit dialled. When testing over an odd test lead the busy or idle condition of the internal link within the odd subscriber unit of the pair in question as far as incoming or outgoing calls are concerned together with the busy or idle condition of the internal link in the even subscriber unit of the pair as far as incoming calls are concerned, are reflected in the marking condition offered by said test lead, while if the even test lead is utilised then the busy or idle condition of the internal link within the even subscriber unit, together with the busy or idle condition of the internal link within the odd subscriber unit of the pair as far as incoming calls are concerned is reflected in the marking on the test lead.

In the present instance where digits 01 have been dialled, the required subscriber will be situated on the even subscriber unit SSU10 and the testing for the busy or idle condition of the four "in" links extending to this subscriber unit will be performed over the 01-00 even group of test leads on to which access can be had over the TS5 wiper and bank. The TS switch is arranged to test only on these four leads and this is effected in the following manner.

If, as already assumed, no other calls have been set up on the board, then all the internal vertical bar links of unit LSU1 will be disengaged so that the vertical bar relays 1CH-4CH will be normal while all the "in" links will be marked free on the associated even test lead. An odd test lead of 11-10 group of test leads to subscriber unit SSU1 of Fig. 3 is shown and is designated X, it being appreciated that other test leads will terminate at the relevant subscriber units in like manner.

Considering now the circuit between the testing relay KR (Fig. 10) and the X test leads, it will be seen that since the DS wipers DS4 and DS5 have been positioned on contacts 11 or 23 according as to whether this switch has been operated from its home position 1 or its second home position 13, then an effective circuit through to the test lead can only be completed as determined by wiper TS4 when the TS switch is occupying positions 18-21, while furthermore wiper and bank DS5 determines that wiper and bank TS5 and not wiper and bank TS6 shall be utilised so that access will be had to the even group of test leads 01-00. It will be furthermore noted that in the circuit to each of the four branch test leads to TS3 there is interposed a normally made contact of each of the four vertical bar relays 1CH-4CH so that if any of these links should be engaged then the circuit to the

associated test lead will be broken and the corresponding "in" link will therefore be marked as busy, since the testing relay is adapted only to switch to a battery marking potential. In the present instance, since all the vertical hold relays of unit LSU1 are normal, access can be had to all four of the test leads and when the TS switch in operating in its self-interrupted circuit reaches contact 18, earth will extend via the low resistance relay KR, contacts *fz1* and *lch2*, bank and wiper TS3, wiper and bank TS4, bank and wiper DS4, wiper and bank DS5, wiper and bank TS5 and the first even test lead of the group which will be marked at the subscriber unit end by a resistance battery such as YB (Fig. 3) of subscriber unit SSU1, over resting contacts of the associated vertical hold relays ASH of the two subscriber units SSU9 and SSU10 forming the selected pair. The ASH relay contacts are included in a series circuit to the marking battery in order to disconnect this battery should the internal vertical bar circuit of either of the two subscriber units be already in use either on an outgoing or an incoming call, but it will be remembered that it was said that if the other subscriber unit of the pair was engaged on an outgoing call, then the "in" link need not be busied and for this purpose the contacts *ash3* of this other subscriber unit are short-circuited by

OP
ASH⁴

contacts if its internal link is involved on an outgoing call.

Relay KR operates quickly and in so doing opens the circuit for magnet TM and completes an operating circuit for relay KRR (Fig. 9) over the following circuit: battery, winding of relay KRR, contact *krr1*, wiper and bank TS1, winding of relay N to earth. Relay KRR in operating locks over its contacts *krr1*, further disconnects the driving circuit for magnet TM at *krr3* and at *krr2* extends earth over wiper TS2 in position 18 to bring up relay *lch* which controls the first vertical link in unit LSU1. This relay in operating operates its associated vertical bar, whereupon since horizontal bar relay *lcp* associated with the calling connecting link circuit AL will have already been operated, and since horizontal bar relay 5TP, not shown, will also have been operated over wiper and bank DS3 in response to the dialling of digit "0," then crossbar contacts

CP 1-3 and TP 1-3
ICH 1-3 and ICH 1-3

will be operated to connect the connecting link circuit through the unit LSU1 to the outgoing negative, positive and private conductors of the first "in" link. At contacts *lch1* relay *lch* prepares a holding circuit for itself, while at *lch2* (Fig. 10) it marks the internal vertical link as busy by disconnecting the circuit to KR over contacts of the banks of the switch TS pertinent to the first one of the four vertical links within the unit LSU1. Relay KR thereupon releases but relay KRR remains held and at contacts *krr4* (Fig. 8) extends earth over common lead 23 and then via the series-connected contacts *sa3* of the SA relays in the two main 50-line subscriber groups 11-50 and 61-00, winding of relay IGS to battery, the contacts *sa3* serving to prevent relay IGS from operating should another subscriber be in process of being connected to a connecting link circuit at this stage and so serving to prevent the effective operation of the equipment FSC.

Relay IGS in operating at contacts *ics1* extends earth over wiper and bank SCS4 to the switching relay SK in the common equipment SCE1 and at contacts *ics3* (Fig. 3) disconnects the earth feed to all subscribers' line relays to prevent the effective initiation of any other call on to a subscriber switching unit during this time, at contacts *ics4* (Fig. 3) battery via resistance YC is connected to common lead 11 extending to the lower incoming "test" winding of all line relays on the board in readiness for switching through to the particular subscriber being called and at *ics6* (Fig. 3) the earth circuit to the SA relays is opened. At contacts *ics2* in the equipment FSC (Fig. 8) earth is extended forward over wiper and bank SCS3, contacts *fz2* and wiper and bank DS7 in the common equipment SCE1, wiper DS7 occupying either of the positions 11 or 23, and then over the Y lead to operate the incoming call horizontal bar relay IP in the particular subscriber unit SSU10 in which the called party is located, the Y lead for unit SSU1 being shown. On operation of relay IP in unit SSU10, the associated horizontal bar is actuated to prepare for the incoming connection. At the same time as earth is extended to the lower winding of relay SK an energising circuit is completed for the slow-to-operate relay G (Fig. 9) via contacts *sk3* and bank and wiper SCS3 to earth over contacts *ics2*. During the operate time of relay G the selected line is tested over the following circuit: earth, *ics1*, SCS4, *g4*, and lower winding of relay SK (Fig. 10), wiper DS8 in position 11 or 23, wiper US7 in position 14 and test lead T, such as that shown in connection with subscriber No. 11, of the called line 01.

Assuming that the called line is free, a battery potential will be connected to the T lead via the common resistance YC and contacts *ics4* (Fig. 5) and then via the lower winding of the called subscribers' line relay which, in the present instance will be relay ISP on subscriber unit SSU10. Relay SK will operate and will lock on its upper winding via contacts *sk1*, *ba9* and *n6* to earth. At contacts *sk2* a guard earth is extended forward over the T lead to operate the called subscriber's line relay ISP whereupon the associated horizontal bar on unit SSU10 is operated so as further to prepare for connection through to the called line. At contacts *sk3* (Fig. 9) the energising circuit for the busy relay G is opened so that this relay is prevented from operating and at *sk4* an energising circuit is completed for the slow-to-operate relay FZR. When relay FZR operates after a short interval, contacts *fzr1* (Fig. 8) disconnect relay BA which commences to release slowly, contacts *fzr2* (Fig. 9) open the circuit of relays SGA and KRR, while contacts *fzr3* (Fig. 10) extend earth over wiper DS6 in positions 11 or 23 and wiper TS7 in position 18 and then over a Q lead to operate the vertical bar relay ASH associated with the first of the four "in" links available to the called unit SSU10, the "in" link and associated internal link in unit SSU10 having been previously selected by the TS switch when testing over lead X. Relay ASH in unit SSU10 in operating operates its associated vertical bar, whereupon sets of contacts such as

IP 1-3 and SP 1-3
ASH 1-3 and ASH 1-3

as in Fig. 3 are closed to extend the calling connecting link circuit AL through the unit LSU1 and over the "in" link to the required line. Earth via contacts *b4* in the link circuit (Fig. 4) is now

extended forward to operate the called subscriber's cut-off relay $1K$, which earth will also serve to hold the vertical bar relay $1CH$ in use in the unit $LSU1$. Relay $1K$ in operating at its contacts $1k3$ extends a guard earth on to the incoming T lead and at contact $1k1$ and $1k2$ completely disconnects the upper winding of the associated line relay from across the line in readiness for the ringing of the called party's bell and of the subsequent answering by the called party.

During this time relay SGA (Fig. 9) will have released and at contacts $sga1$ (Fig. 8) earth is extended upward over lead 17 to bring up relay SD in the link circuit, while at $sga2$ and $sga3$ (Fig. 8) the marking and starting potentials to the common equipment FSC are removed. Relay KRR in releasing at contacts $krr4$ (Fig. 8) removes the start earth from common lead 23 extending to relay ICS in the equipment FSC and this equipment is now free to attend to the completion of other calls which may be held waiting in connecting link circuits at this time, while relay ICS in releasing restores the earth circuit to the various line relays to allow other subscribers on the board successfully to originate calls. At contacts $ics2$ (Fig. 8) and also at $f22$ (Fig. 10) the earth extended forward over wipers and banks $SCS3$ and $DS7$ over the Y lead to operate the incoming relay IP in the called crossbar unit is removed and this relay releases and permits the associated horizontal bar to restore while the pin engaged by the vertical bar relay ASH remains held. Relay SD (Fig. 4) in the link circuit in operating locks over its contacts $sd1$ to the earthed P lead and at $sd3$ opens the energising circuit of the link switching unit relay $1CP$, the associated horizontal bar of which, however, releases while the pin engaged by the vertical bar relay $1CH$ remains held, while at $sd5$ ringing tone is connected up over common lead 22 and over contacts $b3$, $se4$ and $f2$ to the centre winding of relay A from whence it extends by induction on to the incoming lines to the calling party. Relay SD in operating in the link circuit, at its contacts $sd6$ and $sd7$ (Fig. 4), completes a circuit to ring the called party's bell as follows: earthed ringing current generator, common lead 15 , winding of the ring trip relay F , contacts $sd6$ and $f5$, and link switching unit contacts on to the negative line, a return circuit being completed via the called party's bell and positive line via contacts of the link switching unit and contacts $f6$ and $sd7$ to battery via resistance YE , the calling subscriber receiving ringing tone during this time over the circuit previously traced.

On release of relay BA in the equipment $SCE1$ the starting and holding circuits for the time delay relays TA and TZ are opened and at contacts $ba9$ (Fig. 9) the holding circuit for relay SK is opened, while at the same contacts the earth circuit extended forward over wipers and banks $DS6$ and $TS7$ over the Q lead to relay ASH is opened but this relay now remains held over its own contacts $ash1$ (as in Fig. 3) to the incoming earthed P lead. On release of relay SK relay FZR commences to release. At contacts $ba6$ (Fig. 8) a homing circuit is completed for switch DS over wiper and bank $DS1$ from the earthed low resistance relay N and the DS switch wipers are thereupon restored to either of their home positions 1 or 13 . At contact $ba8$ and $ba1$ (Fig. 9) a homing circuit is completed for the switch US over bank and wiper $US2$ and the wipers of this switch are thereupon rotated to the home position 1 . The homing circuit will

have already been completed for switch TS via its bank and wiper $TS1$ (Fig. 9) on the release of relay KRR . Since the homing circuit of each of these switches is completed via the N relay, this relay will remain held until all switches have homed and at its contact $n1$ (Fig. 8) will disconnect the idle marking battery via resistance YH from lead 16 so as to mark the common equipment as busy. On release of relay N the marking battery is replaced on to common lead 16 and the equipment $SCE1$ is now ready for further use by other connecting link circuits associated with unit $LSU1$.

When the called subscriber answers, relay F operates and at contacts $f5$ and $f6$ trips the ringing and extends the lines through. At $f1$ it completes a local locking circuit for itself to earth via contacts $sd8$ and $b4$, while at $f3$ and $f4$ it connects the called subscriber's battery feeding relay D across the lines and at $f2$ it opens the ringing tone circuit.

Conversation now proceeds between the calling and called parties and at the end of conversation the connection will remain held until the calling party hangs up. When this occurs relay A releases and brings down relay B which in turn releases relays SD , F and D to free the link circuit, and releases relay $1CH$ in the link switching unit, while it also releases the called and calling subscribers' cut-off relays and the vertical holding relays in the called and calling subscriber units, whereupon all equipment is free for further use.

Returning again to the testing of the called line, it will be remembered that this is effected by relay SK in the common equipment $SCE1$ during the slow-to-operate time of relay G . If the called line should prove to be busy, then relay SK will not operate and on the operation of relay G the operating circuit for relay SK is disconnected at contacts $g4$ (Fig. 10) and at contacts $g1$ relay FZR is operated to release relays SGA , KRR and BA to initiate release of the common equipment in the manner already described. At contacts $g3$ (Fig. 10) the earth extended forward to operate the vertical hold relay in the called subscriber unit is disconnected and at $g2$ (Fig. 8) earth is extended upward over lead 18 to operate relay SE in the calling link circuit. Relay SE in operating locks over its contacts $se1$, at $se2$ opens the holding circuit of relay $1CP$ and at $se4$ extends busy tone over common lead 14 and contacts $sd4$ and $f2$ to the centre winding of relay A to return busy tone to the calling party. The link circuit remains held until the calling party hangs up when relays A , B and SE release in turn.

Considering now the general functioning of the board, it will have been noted that the equipment FSC is not taken into use from control equipment such as $SCE1$ until the completion of the dialing of the two digits on to that equipment, that is to say, until the equipment is in readiness for testing the required called line. This arrangement is adopted so that if a subscriber should take into use a common equipment via a link circuit and should then delay to dial for a short interval during which time a second common equipment is taken into use by another calling party, then if the dialling operations of the two subscribers should overlap it will not be possible in the case where the two called parties involved are on the same subscriber unit for the two SCE equipments concerned to operate on the one crossbar subscriber unit, since the equipment FSC which controls the testing of a called line from an SCE equipment can only be associated with

one such equipment at a time, which will be the equipment on which the dialling operations are first completed.

In order to prevent the possible clashing of an outgoing and an incoming call on the same subscriber unit, the FSC equipment includes a relay ICS which by operating when an incoming call is to be set up on a subscriber unit disables all line relay circuits as far as calling subscribers are concerned. Conversely, either of the two SA relays common to the two main 50-line subscriber groups on the board by operating, when an outgoing call is to be connected through on a subscriber switching unit, disables the FSC equipment common to the board by opening the ICS relay circuit therein to prevent an incoming call clashing with the outgoing call.

Referring now to the line circuit of Fig. 3, it will be seen that the earth circuit to the various line relays in addition to extending via contacts $ics3$ of relay ICS also extend over contacts of subscriber unit vertical hold relays. As already mentioned earlier in the description there are four "out" links available for each 20-line group of subscribers comprising paired subscriber units such as SSU1 and SSU2, SSU3 and SSU4 and so on, and it will be understood that the inclusion of the vertical hold relay contacts in the earth circuits to the subscribers' line relays is done to ensure that a subscriber shall only be allowed effectively to originate a call provided there is a free "out" link available and shall not be able to do so if for example all four "out" links are in use by the other subscriber unit of the pair even if none of the internal links within the calling subscriber unit are engaged at the time. As far as the ten subscribers 11-10 on subscriber unit SSU1 are concerned it will be seen that the earth circuit to the line relays thereof is completed over contacts $ash4-dsh4$ in unit SSU1 and contact $ash8-dsh8$ in unit SSU2 arranged in the manner shown, the latter contacts each being shunted by normally open contacts at the intersection of the relevant incoming call and vertical hold bars on unit SSU2. These arrangements function in the following manner. Assuming that subscriber No. 11 originates a call and operates the SSU1 unit ASH relay to enable access to be gained to the first of the four available "out" links, then one of the available paths for the earth circuit to the positive lines to all the subscribers 11-10 and 21-20 on units SSU1 and SSU2 will be disconnected at contacts $ash4$ (SSU1) in Fig. 3, and at contacts $ash8$ (SSU1) which are not shown but which are connected in the earth circuit to subscribers 21-20 in the same manner that the contacts $ash8$ (SSU2) are connected for subscribers 11-10. If now subscriber 12 calls, relay BSH on unit SSU1 will be operated to disconnect a second available path in both the above-mentioned earth circuits. If subscriber No. 21 now calls, relay CSH in unit SSU2 will be operated to disconnect the third available path in both earth circuits. If now an incoming call should arrive on unit SSU2 the DSH relay in this unit will be operated to disconnect the last available path as far as subscribers on unit SSU2 are concerned, since all the internal links therein will be engaged. The cross-bar contacts

IP
DSH⁴ (SSU2)

at the intersection of the incoming call bar and the DSH vertical bar and shown in Fig. 3 short-circuit the contacts $dsh8$ (SSU2) in the earth cir-

cuit to subscribers on unit SSU1 so as to enable any one of these subscribers to be able to make a call over the last free "out" link. After this, no further calls can be originated by subscribers on units SSU1 or SSU2 until one of the "out" links again becomes disengaged. Similar considerations apply for the other paired subscriber units of the board, the positive subscribers' lines of which connect via contacts of the relevant vertical "hold" relays to the common earthed lead 10 in similar manner as for the subscribers 11-10.

As regards the starting up of a primary control equipment such as PCE1, it will be remembered that this can only be started up from the associated SA relay via one of the five S relays. In order to prevent two calling conditions appearing simultaneously on any one subscriber unit it will be seen that as soon as a line relay is operated in response to the origination of a call the relevant set of contacts thereof, such as $isp4$ in the case of relay ISP disconnect the operating circuit for any of the other relays 2SP-10SP on the same subscriber unit at the same time as they complete a circuit to the relay IS concerned.

A full description has already been given of a call from subscriber 11 to subscriber 01 and it may be of interest generally to consider what will happen if this connection is followed by one from say subscriber 12 to subscriber 02. In this case the vertical hold relay BSH will be operated on the calling unit SSU1 to give access to the second of the four "out" links available to the paired units SSU1 and SSU2. From the trunking diagram of Fig. 2 it will be seen that the second "out" link connects with a link circuit associated with link switching unit LSU2, which circuit upon being taken into use gives access to common equipment SCE2 which responds to the digits dialled in the same manner as for SCE1 and completes the setting up of the call via the intermediary of the common equipment FSC. The TS switch in equipment SCE2, on being set into operation to find a free "in" link to the group of subscribers of which subscriber 02 forms part, will be unable to find a resistance marking battery via its contact 18 and the X lead since the ASH relay on unit SSU10 will have already been operated by the first call and will have disconnected the marking battery at its contacts $ash2$ (shown in Fig. 3 in connection with unit SSU1). The TS switch will therefore move its wipers onto position 19 where a marking battery will be encountered via the resting contacts of relays BSH in the subscriber units SSU9 and SSU10, after which connection will be made with the called party over the second of the "in" links available to the twenty subscribers on units SSU9 and SSU10. If the second link is already engaged, then the TS switch will rotate to contact 20 to give access to the third "in" link in response to which relay CSH in the called unit SSU10 will be operated.

If the TS switch finds all four links to a required subscriber unit engaged, then it will rotate through to the busy position 22 where it encounters a local battery via resistance YO or YP according to whether an even or odd tens digit has been dialled and relays KR and KRR operate in the usual manner. No circuit can be completed over wiper TS2 in position 22 (as in Fig. 9) to operate a vertical holding relay in the link switching unit however, so that the calling side of the connection cannot be connected through, but instead the earth contacts $krr2$ extend earth over wiper and bank TS2 to bring up

relay G which in a manner already described in connection with a busy subscriber returns busy tone to the calling party and operates relay FZR to release the common equipment for further use.

We claim:

1. In a switching system, a plurality of primary lines, a plurality of links, a plurality of groups of secondary lines, the different lines of each group corresponding respectively to the different ones of said links; a single crossbar switch in which all of said lines and all of said links appear, the contacts of said switch being so arranged that each of said primary lines is selectively connectable to any of said links and each of said secondary lines is connectable only to its corresponding link, apparatus common to all of said groups, means for causing said apparatus to search in any particular one of said groups for an idle secondary line whose corresponding link also is idle, means in said apparatus effective if such a line is found to operate said crossbar switch to condition all of the secondary lines in said particular group for inclusion in a connection, means for also operating said crossbar switch to condition any one of said primary lines for inclusion in a connection, said switch having an individual magnet for each of said links, and means effective while said primary line and said secondary lines are concurrently conditioned to operate the magnet for the link corresponding to said idle secondary line, said crossbar switch thereupon effective to complete a connection from said conditioned primary line to said idle secondary line over the link corresponding to said idle secondary line without completing any other connection between any primary line and any secondary line.

2. In a switching system, a plurality of primary lines, a plurality of links, a plurality of groups of secondary lines, the different secondary lines of each group corresponding respectively to the different ones of said links, a single crossbar switch in which all of said lines and all of said links appear, the contacts of said switch being so arranged that each of said primary lines is selectively connectable to any of said links and each of said secondary lines is connectable only to its corresponding link, said switch having a different selecting magnet for each of said primary lines, means for operating any one of said magnets thereby to condition the primary line corresponding thereto to be included in a connection, said switch also having a different selecting magnet for each said group of secondary lines, means for operating any one of said last magnets while said primary line is thus conditioned, thereby also to condition all the secondary lines of the group corresponding to that magnet to be included in a connection, said crossbar switch having a different holding magnet for each of said links, and means for operating any one of said holding magnets while said primary line and said secondary lines are concurrently conditioned, said crossbar switch thereupon effective to complete a connection only from said conditioned primary line, over the link corresponding to the operated holding magnet, to the conditioned secondary line corresponding to that link.

3. In a switching system, a plurality of primary lines, a plurality of secondary lines, a plurality of links, the different ones of said links corresponding respectively to the different ones of said secondary lines, a single crossbar switch in which all of said lines and all of said links appear, the contacts of said switch being so arranged that each of said primary lines is selectively connecta-

ble to any of said links and each of said secondary lines is connectable only to its corresponding link, said switch having a different selecting magnet for each of said primary lines, means for operating any one of said magnets thereby to condition the primary line corresponding thereto be included in a connection, a magnet common to said secondary lines at times operated while said primary line is thus conditioned, thereby also to condition all of said secondary lines to be included in a connection, said crossbar switch having a different holding magnet for each of said links, and means for operating any one of said holding magnets while said primary line and said secondary lines are concurrently conditioned, said crossbar switch thereupon effective to complete a connection only from said conditioned primary line, over the link corresponding to the operated holding magnet, to the secondary line corresponding to that link.

4. In a switching system, a plurality of primary lines, a plurality of groups of secondary lines, the different secondary lines of each group corresponding respectively to the different ones of said primary lines, a crossbar switch in which all of said lines appear, the contacts of said switch being so arranged that each of said secondary lines is connectable only to its corresponding primary line, apparatus common to all of said groups, means for causing said apparatus to search in any particular one of said groups for an idle secondary line whose corresponding primary line also is idle, means controlled by said apparatus if such a line is found for operating said switch to condition all of the secondary lines in said particular group to be connected over certain of said contacts to their respective primary lines without thus conditioning the secondary lines of any other group, a different switch-operating magnet for each primary line, means controlled by said apparatus while the secondary lines of said particular group are thus conditioned for operating the magnet for the primary line corresponding to the idle secondary line which was found, said crossbar switch controlled by the operation of said magnet thereupon to operate only such of said contacts as are effective to connect the idle secondary line found to its corresponding primary line.

5. In a switching system, a plurality of primary lines, a plurality of groups of secondary lines, the different secondary lines of each group corresponding respectively to the different ones of said primary lines, a set of contacts individual to each secondary line for connecting that secondary line to its corresponding primary line, means operated for conditioning the contact sets individual to all of the secondary lines of any particular group to complete connections from those secondary lines to their respectively corresponding primary lines without thus conditioning the contact sets individual to the secondary lines of any other group, a different magnet for each primary line, each of said magnets operated at times while the contact sets individual to the secondary lines of said particular group are thus conditioned, and means controlled by each magnet, when operated, for operating only the conditioned contact set individual to the secondary line corresponding to that magnet's primary line, whereby a connection is completed between that magnet's primary line and the secondary line in said particular group which corresponds to said primary line.

6. In a switching system, a plurality of primary

lines, a plurality of groups of secondary lines, the different secondary lines of each group corresponding respectively to the different ones of said primary lines, a crossbar switch in which all of said lines appear, the contacts of said switch being so arranged that each of said secondary lines is connectable only to its corresponding primary line, means for operating said switch to condition all of the secondary lines of any one of said groups to be connected over certain of said contacts to their respective primary lines without thus conditioning the secondary lines of any other group, a different switch-operating magnet for each primary line, means for operating any one of said magnets while the secondary lines of said one group are thus conditioned, said crossbar switch controlled by the operation of said one magnet thereupon to complete a connection over certain of said contacts only from that magnet's primary line to the conditioned secondary line corresponding to that primary line.

7. In a switching system, a plurality of groups of lines, a different link for each of said groups, a crossbar switch in which all of said lines and all of said links appear, the contacts of said switch being so arranged that each link is connectable only to lines of the group corresponding to that particular link, and means for causing said switch to control its contacts selectively, thereby to connect any one of said links to any line of the group corresponding to that link without connecting any other line of the same group to said one link.

8. In a switching system, a plurality of primary lines each having an individual secondary line, a crossbar switch in which all of said lines appear, the contacts of said switch being so arranged that each secondary line is connectable only to its individual primary line, a secondary magnet common to all of said secondary lines operated at times to condition said contacts to complete connections from all of said primary lines to their respective individual lines, a different primary magnet for each primary line, each of said primary magnets operated at times while said contacts are thus conditioned, thereby to operate certain of said contacts to complete a connection between the primary line corresponding to the operated primary magnet and the secondary line individual to that primary line.

9. In a switching system, a plurality of primary lines each having an individual secondary line, a crossbar switch in which all of said lines appear, the contacts of said switch being so arranged that each secondary line is connectable only to its individual primary line, and means for causing said switch to control its contacts selectively, thereby to connect any primary line to its individual secondary line without connecting the other primary lines to their respective individual secondary lines.

10. In a crossbar switch wherein any contact set in a coordinately arranged field of contact sets may be operated through the temporary operation of one of a plurality of selecting magnets arranged in one of the coordinate directions and, during the period of operation of said selecting magnet, the operation of one of a plurality of holding magnets arranged in another of the coordinate directions, a plurality of links corresponding respectively to said holding magnets, means for operating two of said selecting magnets concurrently and then releasing both of said magnets, means for operating one of said holding magnets during the concurrent operation of

said two selecting magnets thereby to operate two of said contact sets, said holding magnet effective to remain operated after said release of said selecting magnets thereby to maintain said two sets operated, and a circuit extending over said two contact sets in series with the link corresponding to the operated holding magnet.

11. In a switching system, a single crossbar switch, a plurality of primary lines appearing in said switch, means for operating said switch to condition any particular one of said lines for inclusion in a connection, a plurality of links local to said switch, a plurality of groups of secondary lines appearing in said switch, the different secondary lines in each said group corresponding respectively to the different ones of said local links, apparatus common to all of said groups, means for causing said apparatus to search in any particular one of said groups for an idle secondary line whose corresponding local link also is idle, means in said apparatus effective if such a line is found to operate said switch to condition that line for inclusion in a connection, means in said switch individual to the particular local link which corresponds to the last-mentioned secondary line, said last means operated while both of said lines are thus conditioned to complete a connection from said particular local link to all lines so conditioned, whereby said one primary line and the last-mentioned secondary line is interconnected via said particular link, and said last means effective, after operation, to maintain said connections completed independently of said first means and said third means.

12. In a switching system, a single crossbar switch, a plurality of primary lines appearing in said switch, means for operating said switch to condition any particular one of said lines for inclusion in a connection, a plurality of links local to said switch, a plurality of groups of secondary lines appearing in said switch, the different secondary lines in each said group corresponding respectively to the different ones of said local links, apparatus common to all of said groups, means in said apparatus for receiving different digits, other means in said apparatus for selecting a particular one of said groups in dependence upon the value of a digit received and for searching in that group for an idle secondary line whose corresponding local link also is idle, means in said apparatus effective if such a line is found to operate said switch to condition that line for inclusion in a connection, means in said switch individual to the particular local link which corresponds to the last-mentioned secondary line, said last means operated while both of said lines are thus conditioned to complete a connection from said particular local link to all lines so conditioned, whereby said one primary line and the last-mentioned secondary line is interconnected via said particular link, and said last means effective, after operation, to maintain said connections completed independently of said first means and said third means.

13. In a telephone system, a single crossbar switch, a plurality of subscribers' lines appearing in said switch, a plurality of links local to said switch, a group of incoming trunks over which all calls incoming to said lines are completed, the different ones of said incoming trunks corresponding respectively to the different ones of said links, a group of outgoing trunks over which all calls outgoing from said lines are completed,

the different ones of said outgoing trunks corresponding respectively to the different ones of said links, apparatus operated responsive to an outgoing call to search for an idle outgoing trunk whose corresponding local link also is idle and operated responsive to an incoming call to search for an idle incoming trunk whose corresponding local link also is idle, means in said apparatus effective, if such a trunk is found during a search resulting from an incoming or outgoing call, to operate said crossbar switch to condition that trunk for inclusion in a connection, means for also operating said switch to condition any particular one of said subscribers' lines for inclusion.

5 in a connection, means in said switch individual to the particular local link which corresponds to the conditioned trunk, said last means operated while said trunk and said line are thus conditioned to complete a connection from said particular local link to all lines and trunks so conditioned, whereby said one subscriber's line and said trunk are interconnected via said particular link, said last means effective, after operation, to maintain said connections completed independently of said first means and said second means.
